UNITED STATES PATENT OFFICE

2,661,517

CONCRETE FORM

Jack Rue Findley, Bellflower, Calif.

Application June 29, 1951, Serial No. 234,298

6 Claims. (Cl. 25—131)

1

This invention relates to new and useful improvements in concrete forms and the primary object of the present invention is to provide a concrete form including a pair of slidably connected, telescoped, channel-shaped sections that are adjustable longitudinally of each other by rods that also anchor the sections to the ground.

Another important object of the present invention is to provide a concrete form of the aforementioned character wherein the rods each carry a means for supporting and forcing a waler strip against the sections to reinforce and strengthen the sections.

A further object of the present invention is to provide a concrete form that is extremely light in weight to facilitate convenient carrying thereof and which is quickly and readily adjusted in length for various types of work.

A still further aim of the present invention is to provide a concrete form that is simple and practical in construction, strong and reliable in use, efficient and durable in operation, inexpensive to manufacture, convenient to install, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a front elevational view of one embodiment of the present form;

Figure 2 is a plan view of Figure 1;

Figure 3 is a transverse vertical sectional view of the form in use;

Figure 4 is an enlarged horizontal sectional view taken substantially on the plane of section line 4—4 of Figure 3 but showing the waler strip and side member in dotted lines;

Figure 5 is a transverse vertical sectional view of another embodiment of the present invention in use;

Figure 6 is a perspective view of the outer section of the side member shown in Figure 5; and,

Figure 7 is a perspective view of the inner section of the side member shown in Figure 6.

Referring now to the drawings in detail, wherein for the purpose of illustration, there is disclosed a preferred embodiment of the present invention, the numerals 10 and 12 represent the side members of the form shown in Figures 1—4 inclusive. The side members 10 and 12 include inner channel shaped sections 14 and 16, and outer channel shaped sections 18 and 20.

2

The channel sections 14 and 16 are provided with upper flanges 22 and 24, and lower flanges 26 and 28 having offsets 30 and 32. The channel sections 18 and 20 are also provided with upper flanges 34 and 36, and lower flanges 38 and 40 having offsets 42 and 44.

The channel shaped sections 14 and 16 are slidably telescoped in the channel shaped sections 18 and 20, and the sections of member 10 are disposed in back to back, spaced relationship to the sections of the member 12. The flanges 34, 36 and the portions 42, 44 of flanges 38, 40 are formed with longitudinally spaced slots S for selectively registering with longitudinally spaced apertures A in the flanges 22, 24 and the portions 30, 32 of flanges 26, 28.

Vertical rods 46 extend through certain of the slots S and the apertures A in registry with these slots. The lower ends of the rods 46 extend well below the flanges 38, 40 to penetrate the ground and hold the members 10 and 12 spaced parallel to each other and against sliding movement. The rods 46 extending through the member 10 are connected to the rods 46 extending through the member 12 by connector wires 48 having terminal eyes 50 that fit over the upper ends of the rods.

Means is provided for clamping waler strips W against the sections 14, 16, 18 and 20. This means comprises a sleeve 52 that is slidably received on each rod. Set screws 54 carried by the sleeves engage the rods to adjust the sleeves vertically on the rods. Horizontal arms 56 extend from the sleeves to underlie the waler strips and vertical cams 58 attached to the sleeves and arms will ride against the strips W to force the same against the sections 14, 16, 18 and 20 as the rods 46 are rotated by hand grips G at the upper ends of the rods.

The outer edges of the flanges 22, 24, 34 and 36 are turned down and the outer edges of the flange portions 30, 32, 42 and 44 are turned upwardly. The downturned edges of the flanges 34 and 36 are connected to the upturned edges of the flanges 42 and 44 by vertical reinforcing and strengthening straps 60 that are welded to the outer faces of these bent edges. The downturned edges of the flanges 22 and 24 are connected to the upturned edges of the flanges 30 and 32 by vertical reinforcing and strengthening straps 62 whose ends are welded to the inner faces of these turned edges.

In practical use of the form shown in Figures 1—4 inclusive, the members 10 and 12 are retained spaced parallel to each other by the rods 46 and

the length of the members 10 and 12 is accomplished by the rods 46 in the manner previously described. The offsets 42 and 44 rest upon the ground and the lower portions of the members 10 and 12 enter a ditch D. Concrete C is then poured between the form members 10 and 12 and passes beneath the flanges 38 and 40, as shown in Figure 3.

The concrete contacting faces of the members 10 and 12 are greased to permit convenient removal of the form members 10 and 12 after the concrete has hardened.

Reference is now directed to Figures 5, 6 and 7 wherein there is illustrated the present concrete form in slightly different construction. In this embodiment the side member is designated by the numeral 100 and comprises inner and outer channel spaced sections 102 and 104 with the inner section 102 telescoped within the outer section 104.

The section 102 includes upper and lower flanges 106 and 108 and the section 104 includes upper and lower flanges 110 and 112. The outer edge of the flange 106 is turned downwardly and the outer edge of the flange 108 is turned upwardly, and these turned edges are joined by vertical reinforcing and strengthening straps 114 whose ends are welded behind the turned edges. The outer edge of the flange 110 is turned downwardly and the outer edge of the flange 112 is turned upwardly and these turned edges are joined by vertical straps 116 whose ends are welded to the outer faces of these turned edges.

The flanges 110 and 112 are formed with longitudinally spaced slots S' for selectively registering with longitudinally spaced apertures A' in the flanges 106 and 108.

The rods 46' are extended through certain slots S' and the apertures A' in registry therewith to longitudinally adjust the sections 102 and 104 relative to each other. Collars 52' are adjustable vertically on the rods 46' by set screws 54' and the sleeves carry horizontal arms 56' and vertical cams 58'. The arms 56' support a waler strip W' and the cams 58' will ride against the strip W' to force the strip W' against the sections 102 and 104 when the rods 46' are rotated by hand grips G' at the upper ends of the rods 46'.

The form 100 is shown in use in Figure 5 wherein the poured concrete C' engages the vertical walls of the sections 104 and 106.

Having described the invention, what is claimed as new is:

1. A concrete form comprising a side member composed of telescoped inner and outer channel shaped sections, each of said sections having upper and lower flanges, the flanges of one section having longitudinally spaced slots therein and the flanges of the other section having longitudinally spaced apertures therein for selectively registering with the slots, means extending through selected slots and apertures to maintain the sections adjusted longitudinally of each other, and cam means carried by said first named means for clamping a waler strip against the sections.

2. The combination of claim 1 wherein the first named means comprises a plurality of vertical rods having lower ends extending below the lower flanges of said sections to penetrate the ground and hold the member against movement.

3. A concrete form comprising a side member composed of telescoped inner and outer channel shaped sections, each of said sections having upper and lower flanges, the flanges of one section having longitudinally spaced slots therein and the flanges of the other section having longitudinally spaced apertures therein for selectively registering with the slots, means extending through selected slots and apertures to maintain the sections adjusted longitudinally of each other, said means comprising a plurality of manually rotatable vertical rods having lower ends extending below the lower flanges of said sections to penetrate the ground, horizontal arms vertically adjustably mounted on the rods, a waler strip supported on the arms, and vertical cams on said arms for camming against the waler strip as the rods are rotated to force the waler strip against the sections.

4. A concrete form comprising a pair of parallel side members, each of said side members including a pair of inner and outer telescoped channel shaped sections, said sections each having upper and lower flanges, the sections of one member being disposed in back to back relationship to the sections of the other member, the flanges of each outer section having a plurality of longitudinally spaced slots, the flanges of each inner section having a plurality of longitudinally spaced apertures therein for selectively registering with said slots, manually rotatable vertical rods extending through selected slots and the apertures in registry with the selected slots to maintain the inner and outer sections of each member adjusted longitudinally of each other, and means carried by said rods for clamping waler strips against the sections.

5. The combination of claim 4 wherein said means comprises a horizontal waler strip supporting arm carried by each rod and a vertical cam on each arm for camming against a waler strip supported on the arms as the rods are rotated.

6. The combination of claim 5 and connecting wires joining the rods extending through the sections of one member to the rods extending through the sections of the other member.

JACK RUE FINDLEY.
